PROCESS FOR THE TREATMENT OF
HYDROCARBONSWalter A. Schulze, Bartlesville, Okla., assignor to
Phillips Petroleum Company, a corporation of
Delaware

Application August 29, 1941, Serial No. 408,876

2 Claims. (Cl. 260—680)

This invention relates to improvements in the catalytic dehydrogenation of hydrocarbons to produce olefins and diolefins. It relates more particularly to an improved process of producing butadiene by catalytic dehydrogenation of normal butane.

This is a continuation-in-part of my co-pending application Serial No. 353,962, filed August 23, 1940.

In the production of the valuable diolefin butadiene from normal butane, two catalytic dehydrogenation reactions are involved; namely, the conversion of butane to mono-olefinic butenes, and the conversion of butenes to the diolefinic butadiene. These two reactions may be combined in a single stage operation in which butane is charged and butadiene extracted while a large volume of butane-butene recycle is handled. It is a disadvantage of this type of operation that the optimum conditions of temperature and pressure are quite different for the two reactions. Thus, in a process which depends on concurrence of the two reactions, a compromise on operating conditions is necessary whereby neither reaction is most efficiently carried out.

When a two-stage catalytic dehydrogenation process is employed, butenes are produced in the first stage under conditions of temperature, pressure and reactant concentrations most suitable for their formation with a minimum of decomposition to undesired products. The butenes are then separated by suitable means and subjected to a further dehydrogenation step with conditions carefully selected to allow the use of higher conversion temperatures along with higher concentrations of unsaturated hydrocarbons and the relatively unstable products. The dehydrogenation of butenes is accordingly carried out at low partial pressures of reactants and hence of diolefinic products to avoid excessive decomposition.

One expedient for obtaining the necessary low partial pressures of butenes during dehydrogenation is the use of a suitable inert diluent gas whereby the partial pressure of butenes may be varied with the total pressure of the dehydrogenation system. In this connection it has been found that the lower-boiling hydrocarbon gases are satisfactory diluents provided that said gases are relatively easily separated from the C₄ reactants and products, and that the diluents are sufficiently inert so that dehydrogenation of the diluent does not produce hydrogen in quantities large enough to affect the equilibrium in the dehydrogenation of the C₄ hydrocarbons. Hydrocarbon fractions comprising propane have been

found satisfactory in applications involving the dehydrogenation of butane, but the minor dehydrogenation of propane during the conversion of propane-butene mixtures at low partial pressures of said butenes has proved disadvantageous.

In my co-pending application Serial No. 353,962 I have disclosed a method of operation in which the predominantly unsaturated C₃ fraction formed in the dehydrogenation of n-butane in the absence of a diluent is separated with the butene-1 formed in said dehydrogenation, and the combined propylene-butene-1 mixture is the charge to the second dehydrogenation step. This C₃ fraction then serves as a portion of the diluent necessary to produce the desired partial pressures of butenes in the charge to the second dehydrogenation. This process combines the physical advantages of the C₃ diluent and the hydrogen-acceptance capacity of the propylene formed in the first dehydrogenation. However, since the volume of C₃ hydrocarbons produced in the first stage is insufficient to reduce the butene partial pressure to the desired range, additional C₃ material must be provided and a continuous recycle of the required volume maintained. This recycling of propane involves compression, fractionation and storage facilities for the condensation, separation and return of the diluent to the second dehydrogenation step.

Thus, although the physical characteristics of C₃ hydrocarbons are superior to those of the other gaseous hydrocarbons for my purposes, the described use of propane-propylene mixtures alone as a diluent involves a large investment in expensive compression and/or cooling facilities for the condensation of the propane. The compression and cooling costs for the condensation of large volumes of propane at high pressures and/or low temperatures is an important item in plant equipment and operating costs.

I have now discovered a method of operation which retains the advantages of the C₃ hydrocarbon diluent as produced in the first dehydrogenation stage and as separated with butene-1 as the charge to the second dehydrogenation stage. By this method of operation the C₃ hydrocarbon by-product is utilized to advantage, and a depropanizing fractionation on the products from the first dehydrogenation may be dispensed with.

In addition, my process may be operated so as to reduce greatly the volume of propane diluent circulated in the second dehydrogenation step or to eliminate completely the propane recycling operation. This is accomplished in one embodiment of the present invention by adding to the

propylene-butene-1 charge sufficient water vapor to produce the desired butene partial pressure. The reduction in the volume of propane handled and the use of the easily condensable water vapor result in a drastic reduction in the compressor requirements of a plant using my process. This savings in plant equipment and operating costs is reflected in the cost of the product and the economic value of the process. Furthermore, improved dehydrogenation and longer catalyst life at higher temperatures are obtained due to the peculiar benefits of the propylene-water vapor diluent combination.

It is an object of this invention to provide improved methods for the catalytic dehydrogenation of hydrocarbons. Another object of this invention is to provide a catalytic process for the production of butadiene which allows longer operating cycles and greater economies in plant equipment and operating costs than similar methods heretofore known. A further object is to utilize by-products from a first dehydrogenation stage as diluents in a second dehydrogenation stage. A still further object is to provide a diluent comprising propylene and water for the dehydrogenation of butenes whereby the production of butadiene therefrom is facilitated. These and other objects of my invention will be evident from the following disclosure.

I have found that by operating an initial catalytic dehydrogenation step at low pressures to convert butane to butenes in the absence of any diluent a considerable quantity of C_3 hydrocarbons occurs at conditions which afford a satisfactory yield of butenes per pass. This indicates that a number of reactions involving butane proceed according to the following equations:

The reactions illustrated by the first two equations are of greatest importance since they account for the formation of normal butenes (both isomers), and propylene. The first three reactions are so-called primary reactions while the fourth is a secondary reaction dependent upon primary reaction products. Thus, propylene is present to a considerable degree in the effluents whereas the secondary product, propane, is not given much chance to form and the amount is relatively small. While some propylene will be formed in practically all operations in which a satisfactory per pass yield of butene will be obtained from butane, it is preferable to utilize temperatures and catalysts of such nature that appreciable quantities of propylene will be formed without substantially affecting the butene yield. Such conditions of operation are hereinafter more fully described. In the event it is desired to operate in a manner which will result in little or no propylene formation, propylene from an outside source may be admixed with the diluent as described below for introduction into the second dehydrogenation stage.

If desired it will be possible to conduct the process in a single stage, starting with either butane or butene, and introducing a propylene-containing diluent as described below into said single stage. When starting with butane for the production of butadiene, more severe catalytic treatment will be required.

In treating an effluent gas containing all the reaction products from the dehydrogenation of butane to segregate a suitable charge for a second catalytic dehydrogenation step, a gas containing compounds having the following boiling points must be processed with an initial separation as indicated.

Component	Boiling point, °F. (760 mm. Hg)
Hydrogen	-253.7
Methane	-155.1
Ethylene	-126.9
Ethane	-52.6
Propylene	-48.1
Propane	20.0
Butene-1	31.2
Butane	{ Trans- 33.8 Cis- 38.5
Butene-2	

This initial separation may be accomplished by compressing and cooling the vapors to condense the C_3 and C_4 hydrocarbons with a possible secondary recovery operation to strip C_3 hydrocarbons out of the uncondensed gases if desired. The required pressure will of course depend on the degree of cooling applied, and usually pressures of 250-350 pounds gage are sufficient. Some C_2 hydrocarbons will remain in the liquid condensate, but the amount retained is not harmful and may be reduced during subsequent fractionation of the condensate.

By fractionation of the condensate I obtain a satisfactory charge to the second dehydrogenation step of my process. This fractionation may be accomplished in one or in a sequence of columns. In one case a highly efficient fractionating column is used to separate C_3 hydrocarbons and butene-1 overhead while the higher-boiling C_4 hydrocarbons are the kettle product which I recycle with fresh butane feed to the catalyst in my first step. The overhead product containing propylene, propane and butene-1 will have a composition approximating the following:

	A (volume per cent)	B (volume per cent)
Propylene	15	20
Propane	2	4
Butene-1	83	76

Analysis "A" shows that under one set of conditions about 85 per cent of the C_3 fraction is propylene, while the volume per cent of C_3 hydrocarbons is 17 per cent of the total. I have also noted that by choosing even more severe conditions for the dehydrogenation of butane that a larger percentage of C_3 hydrocarbons may be produced with satisfactory ratio of propylene to propane. In this case, I may produce in my first dehydrogenation step a propylene-butene-1 fraction containing about 25 per cent of C_3 material of which the major portion is propylene as shown by analysis "B" above. Thus, by proper regulation of operating conditions, a charge stock for the second stage dehydrogenation may be produced containing from about 10 to 30 per cent propylene.

The propylene-butene-1 fraction is charged to the second dehydrogenation step for the conversion of butenes to butadiene. To the fresh feed is added recycle butenes and sufficient water vapor to produce the desired butene partial pressure. Some recycled C_3 hydrocarbons may also

be added either directly or indirectly to the feed stream. The effluents from the catalytic treatment are cooled to condense the water vapor, and after the separation of water the hydrocarbons are further compressed and/or cooled to condense the C₄ hydrocarbon fraction. Uncondensed gases may be vented or passed to the vapor recovery system serving both dehydrogenation steps for the recovery of C₃ and heavier hydrocarbons. The condensate is then processed by any of the conventional methods for the extraction of butadiene, and the unconverted butenes are returned to the catalyst. A fractionating or stripping operation to remove C₃ hydrocarbons may be included just prior to the butadiene extraction step.

The process may be more readily understood by reference to the accompanying drawing, which is a diagram of one form of apparatus in which the invention may be practiced.

In the figure, butane enters the system through line 1 and is pumped by pump 2 and line 3 into heater 4 where the temperature is raised to the desired level. The heated vapors then pass through line 5 to catalyst cases 6 filled with a suitable dehydrogenation catalyst. The effluent vapors leave the cases through line 7 and enter heat exchange system 8 wherein they are cooled to the desired level. A portion of the effluent vapors may be returned to the charge line 3 ahead of the heater through line 7—A and a compressor (not shown).

Leaving 8 the cooled vapors enter the compressing section 10 through line 9. This section comprises usually at least two stages of compression with compressors 11 and accumulators 12. The liquid accumulator products pass through line 13 to the fractionating column 14. The uncondensed gas comprising hydrogen, C₃ and lighter hydrocarbons, and other gases leave the accumulator by line 15 and pass to a vapor recovery plant 16. This plant may be of the oil absorption type and serves to recover C₃ and heavier hydrocarbons from the lighter gases. The recovered C₃ and C₄ material is returned to fractionator 14 through line 17, while the light gases are removed by line 18. If desired, a small amount of the hydrogen-containing gas may be returned to the butane charge line through line 18—A.

Fractionator 14 represents the fractionating equipment used to segregate the butene charge to the second dehydrogenation step. This may be operated to take overhead C₃ hydrocarbons and the lowest boiling butene, namely, butene-1. The propylene-butene-1 fraction passes through line 19, condenser 20 and into accumulator 21, from which uncondensed gases pass by line 22 to the vapor recovery plant. A portion of the condensate is returned to the columns as reflux by pump 23 and line 24, while the excess liquid goes through line 25 to storage vessel 26. In this fractionation, the kettle product comprising butenes-2 and unconverted n-butane is taken through line 27 and pump 28 and returned to the raw feed stream ahead of the heater.

The fresh butene charge from vessel 26 is fed through line 29 and pump 30 to heater 31 together with recycle butenes from line 54 and sufficient diluent to produce a reduced butene partial pressure in the desired range. This diluent comprises water vapor added through line 32 and C₃ hydrocarbons. The C₃ hydrocarbon diluent which is predominantly propylene comprises that produced and separated in the

first dehydrogenation step plus varying amounts which may be added through line 58 from an external source indicated by line 60 or from the de-propanizing column following the second dehydrogenation step through lines 47 and 59. If desired, small amounts of hydrogen-containing gases may be added through lines 44 and 59 to line 58.

The butene charge diluted with C₃ hydrocarbons and water vapor is heated in heater 31 to the required temperature and passes by line 33 to catalyst cases 34 filled with a suitable dehydrogenation catalyst. The treated vapors leave the cases through line 35 and pass to cooling system 36 wherein the temperature is lowered sufficiently to condense the water vapor, after which the cooled material passes through line 37 and the water is trapped out and removed from separator 38 by line 39. The hydrocarbon gases leaving separator 38 by line 40 are compressed in compressor 41 and pass through line 42 to accumulator 43. The condensate from 43 comprising C₃ and C₄ hydrocarbons may then pass through line 45 to column 46 wherein C₃ hydrocarbons may be separated as an overhead product. The uncondensed gas from accumulator 43 is taken through line 44 and may be vented from the system or passed through line 59 and processed in the vapor recovery plant 16 or elsewhere along with the overhead product from column 46 passing through line 47. The liquid product from the kettle of 46 is taken through line 48 with necessary cooling (not shown) to butadiene extraction unit 49 which may embody any of the known processes for extracting butadiene from C₄ hydrocarbon mixtures. The butadiene concentrate is removed by line 50 to storage vessel 51. The hydrocarbons remaining after the extraction of butadiene are removed through line 52 and pump 53 which recycles the stream through line 54 to the catalytic treatment.

Alternately, the condensate from accumulator 43 may pass through line 55 to drying and refrigeration unit 56 and thence through line 57 to butadiene extractor 49 without intervening fractionation or stripping. The separation of C₃ hydrocarbons may be accomplished by higher temperatures and/or lower pressures on accumulator 43 to a degree commensurate with satisfactory retention of C₄ hydrocarbons.

In the first stage of my process pressures of 15 to 50 pounds gage are employed for the dehydrogenation of butane. Temperatures and pressures are selected within a range suitable for the catalyst used, and temperatures within the range of 1000 to 1200° F. are ordinarily employed. At these conditions flow rates of the order of 1 to 10 liquid volumes of butane per hour per volume of catalyst are usually maintained, although at the higher temperatures still higher flow rates may be used. Particular conditions of flow rates, temperature and pressure are usually chosen to conform to the characteristics of the specific catalyst employed.

The catalysts which are useful in the first stage of my process are those having suitable activity in promoting the dehydrogenation of paraffin hydrocarbons at the preferred operating temperatures. These may include the natural and/or synthetic metal oxide catalysts either alone or mixed with each other or promoted by oxides of metals of groups IV to VIII of the periodic system.

In the operation of the second dehydrogena-

tion step, the butene charge is diluted with sufficient C₃ hydrocarbons and water vapor to maintain butene partial pressures within the preferred range of 0.2 to one atmosphere. The volume of C₃ hydrocarbons included may vary rather widely from the minimum volume produced in the first dehydrogenation step up to larger volumes provided by recycling C₃ material from the second stage effluents or by addition from an external supply. In most cases, the volume of C₃ hydrocarbons will be minor compared to the volume of water vapor, although this volume ratio may be varied with specific operations and within the terms of this disclosure. In general, it is preferable that the total input to the second stage dehydrogenation should be over 50 per cent steam, and up to 65 per cent or higher is desirable. However, any appreciable amount of water vapor will contribute toward improved results to a certain extent, and therefore practically any desired amount may be used, the proportions referred to merely representing preferred conditions.

The effluents from this second stage treatment are cooled to condense and separate water and the hydrocarbon gases are then compressed and/or cooled to condense the higher-boiling components. The condensate comprises the C₄ hydrocarbons with varying amounts of C₃ hydrocarbons according to the conditions of condensation. The uncondensed gases usually comprising C₃ and lighter material having been separated, the condensate may then be fractionated for complete removal of C₃ hydrocarbons, and the C₄ liquid then treated for the extraction of butadiene. The unconverted C₄ hydrocarbons are recycled to the catalyst and after steady-state conditions are established, a volume of C₃ hydrocarbons approximately equal to the propylene and propane formed in the two stages of dehydrogenation is removed from the system at a point following the second catalytic treatment.

An alternative feature of the second stage of my process is that the C₄ condensate subsequent to at least a partial separation of C₃ and lighter material as uncondensed gases may be dried and cooled to suitable sub-atmospheric temperatures and treated directly for the extraction of butadiene. In this case, the de-propanizing step is eliminated, and the compression and condensation steps are operated so as to prevent any substantial losses of C₄ hydrocarbons in the uncondensed gases. Any C₃ hydrocarbons recycled with the unconverted butenes to the catalyst are not harmful as long as the propane concentration is not allowed to pyramid.

If C₃ hydrocarbons alone comprise the diluent in the second stage of my process, the C₃ fraction separated following said second stage is the equilibrium propane-propylene mixture and is predominantly propane. This equilibrium mixture under the operating conditions described herein will ordinarily be approximately 20 per cent propylene and 80 per cent propane, with the actual values being dependent, of course, on the temperatures involved. However, when water vapor is used as the major part of the diluent according to the present invention, a portion of the excess of propylene provided in the C₃ fraction from the first stage may survive the second dehydrogenation stage. Thus, it may be desirable to recycle minor amounts of this C₃ fraction to the second stage until that concentration of C₃ hydrocarbons is approached which will yield equilibrium

propane-propylene mixtures in the treated vapors in the presence of water vapor. In this manner, the propylene is most efficiently utilized in its function of promoting the dehydrogenation of butenes and simultaneously suppressing the dehydrogenation of propane.

Ethane and lighter gases must be satisfactorily removed from the effluents of the first stage in order to facilitate the segregation of the propylene-butene-1 stock by fractionation. Compression of the vapors to fairly high pressures is one method of accomplishing this de-ethanizing step, but other variations of this method are possible. For example, refrigeration of the vapors prior to a low-temperature flashing operation at lower pressures to remove ethane and lighter material is possible. Fractionation of the condensate to separate propylene and butene-1 may be accomplished in a single column, or if desired the C₃ hydrocarbons may be separated in one column and butene-1 in another column and the fractions combined ahead of the second dehydrogenation step.

The overhead fraction will contain minor amounts of dissolved light hydrocarbons, but these may be retained as diluents. The other C₄ hydrocarbons likely to be included are isobutane and isobutene, but in the process described the amounts of these compounds formed are minor.

When other methods are used to segregate the butene charge to the second stage, the C₃ fraction may be separated in a separate fractionation operation. For example, when the higher-boiling butenes-2 are being separated by a fractionation producing said butenes as a kettle product while butene-1 and n-butane are taken overhead and recycled to the first stage dehydrogenation, the C₃ fraction is removed from the butene-1-n-butane fraction, usually before the butene separation, and is later added to the butenes-2 charge to the second dehydrogenation. These and other modifications of the procedure for obtaining the butene stock for the second dehydrogenation will be apparent to those skilled in the art, and are applicable within the disclosure of the present invention.

The second stage of dehydrogenation is operated at partial pressures of butenes in the range of about 0.2 to one atmosphere with total pressures usually between zero and 50 pounds gage. Low total pressures are desirable in order to operate with maximum volume concentrations of C₄ material.

Higher temperatures are usually required in the second stage than in the first stage to obtain satisfactory yields of butadiene from butenes. Thus, temperatures in the range of 1100 to 1300° F. are ordinarily employed. Flow rates in the second stage are usually maintained between 1 and 10 liquid volumes of charge per hour per volume of catalyst. The particular combination of flow rate, temperature and pressure for a specific operation will depend on the catalyst used and the degree of conversion.

The catalysts used in the second stage are those of satisfactory activity at the preferred temperature range which do not cause excessive decomposition and/or polymerization of reactants or products. These may include natural and/or synthetic metal oxide catalysts with or without promoting agents. Of particular value are bauxite and bauxite deactivated with barium hydroxide according to co-pending application Serial No. 353,961, filed August 23, 1940, of which I am a co-inventor.

In the catalytic dehydrogenation of butenes over the above-mentioned catalysts certain benefits have been noted from the use of water vapor as a diluent. Thus, while it has been stated in the prior art that the presence of large quantities of water vapor was detrimental to the activity of metal oxide dehydrogenation catalysts, this effect has been eliminated in connection with the catalysts and method of operation of my process. On the other hand, a prolonged period of maximum activity has been obtained with the propylene-water vapor diluent when used according to the terms of this disclosure. The exact reason for this beneficial effect is not known, nor is such knowledge essential to the practice of the invention. It is proposed, without limiting the operation of my process thereto, that the water vapor suppresses to some extent the poisoning of the catalyst due to tar and/or coke deposition thereon, and that the catalyst activity is thus prolonged. Also, the dehydrogenation reaction is promoted to the extent that hydrogenation of the propylene occurs during the catalytic treatment.

Improved dehydrogenation by my process is noted even at temperatures in the highest portion of the dehydrogenation range. Thus at temperatures of 1220 to 1300° F. which give maximum conversion of butenes per pass, the decomposition of butenes to light gases and coke is decreased in the presence of the propylene-water vapor diluent and the ultimate yield of butadiene on the basis of the C₄ charge is correspondingly improved. The effect of the combination propylene-water vapor diluent in prolonging catalyst activity and permitting higher conversion per pass at higher temperatures is more pronounced than would be expected from results obtained using either component separately. The proposed function of the propylene in suppressing the hydrogenation of the butenes is apparently complementary to the oxidative function of the water vapor in suppressing carbon deposition on the catalyst surfaces.

Butadiene separation may be carried out by any conventional method, such as chemical extraction by suitable solutions, such as cuprous salt solutions, solvent extraction by sulfur dioxide and/or other solvents or other satisfactory physical extraction and/or separation processes.

The butene stream which is recycled to the second catalytic treating section comprises the equilibrium mixture of the normal butenes, containing both butene-1 and butene-2. This mixture, however, is also readily dehydrogenated to butadiene under essentially the same conditions as butene-1 and is quite suitable for inclusion in the butene-1 charge. When operating with a non-hydrogenatable diluent, a small proportion of butane is also formed. However, with propylene-rich diluent used in my process the quantity of butenes so hydrogenated is suppressed. Any butane formed is readily included in the recycle stream without trouble.

The following example will further illustrate the manner in which my process may be carried out.

Example

Normal butane was dehydrogenated over a calcined bauxite catalyst at a temperature of 1100° F. and 30 pounds gage pressure in the apparatus shown in the drawing. A flow of one liquid volume of butane per hour per volume of catalyst was employed. Conversion of the butane was about 20 per cent per pass and the effluents contained about 15 weight per cent butenes, 5 weight

per cent of ethane and lighter gases and about two weight per cent of C₃ hydrocarbons, almost exclusively propylene.

The effluents were substantially de-ethanized and then fractionated in a column operated so as to take butene-1 and the C₃ hydrocarbons overhead while butenes-2 and unconverted n-butane were taken from the bottom of the column and returned to the dehydrogenation catalyst along with fresh n-butane feed. When a constant recycle ratio was established, the 20 per cent per pass conversion of n-butane produced about 13 weight per cent of butene-1 due to combined dehydrogenation of n-butane and isomerization of butenes-2 in the recycle stream. As the run progressed, catalyst activity was maintained by slowly increasing the conversion temperature up to about 1150° F. at which point the run was discontinued for regeneration of the catalyst.

20 The propylene-butene-1 product from the first dehydrogenation was preheated and charged to the second stage combined with recycled C₃ hydrocarbons and sufficient added water vapor to reduce the concentration of butene-1 to about 25 volume per cent. The charge was as follows:

	Volume per cent
Butene-1	25
C ₃ hydrocarbons	15
Steam	60

25 The charge mixture was heated to 1190° F. and passed at 5 pounds gage pressure over a catalyst prepared by impregnating calcined bauxite with 5 per cent by weight of barium hydroxide. At a flow rate of 4 liquid volumes of charge per hour per volume of catalyst about 40 per cent conversion of butenes per pass was obtained.

30 Conversion of butenes to butadiene amounted to about 50 per cent of the total conversion, with the rest being recovered as C₃ and lighter gases.

40 The effluents were cooled to condense the water vapor and after the separation of the water, the hydrocarbon gases were compressed and cooled to condense the C₄ components. About 45 volume

45 per cent of the hydrocarbon gases was removed as C₃ and lighter material, the balance corresponding to about 55 volume per cent of C₄ hydrocarbons or 80 weight per cent of the butene charge was processed for the extraction of butadiene. The butadiene recovered corresponded to about 20 weight per cent of the butene charge and to about 25 per cent of the C₄ condensate, the remaining 75 per cent being recycled to the catalyst.

50 I claim:

1. In the conversion of butenes to butadiene the improvement comprising passing butenes into contact with a dehydrogenation catalyst under conditions suitable for dehydrogenation of butenes to butadiene, providing in the butene feed

60 such an amount of C₃ hydrocarbon diluent comprising propylene and propane that the ratio of propylene to propane in the butene feed is substantially greater than the corresponding equilibrium ratio prevailing under the dehydrogenation

65 conditions, admixing with the hydrocarbons a quantity of steam at least equal in volume to the volume of the hydrocarbon feed, separating butadiene from the effluents of the dehydrogenation, and recycling unconverted butenes from the effluents of the dehydrogenation to the dehydrogenation catalyst as part of the butene feed.

70 2. In the conversion of butenes to butadiene the improvement comprising passing butenes into contact with a dehydrogenation catalyst at tem-

peratures within the range of 1100° F. to 1300° F. for dehydrogenation of butenes to butadiene, providing in the butene feed such an amount of C₃ hydrocarbon diluent comprising propylene and propane that the weight ratio of propylene to propane in the butene feed is substantially greater than 1:4, admixing with the hydrocarbons a

5 quantity of steam at least equal in volume to the volume of the hydrocarbon feed, separating butadiene from the effluents of the dehydrogenation, and recycling unconverted butenes from the effluents of the dehydrogenation to the dehydrogenation catalyst as part of the butene feed.

WALTER A. SCHULZE.
